MULTIPLE JOINT EXTENSION UNION

Joseph E. Guildford, Regina, Saskatchewan,
CanadaApplication November 19, 1934, Serial No. 753,722
In Canada April 6, 1934

7 Claims. (Cl. 285—122)

My invention relates to improvements in a multiple joint extension union, and the objects of my invention are to enable the removal of a closet elbow without removing the closet tank, in order 5 to permit the removal of a closet bowl for repairs to piping, or to clear stoppages in the bowl, etc.

My invention may be installed in conjunction with an ordinary closet elbow to replace a worn out closet elbow, without removing the closet tank 10 or closet bowl.

My invention may be installed on the horizontal portion of a closet elbow as shown in the accompanying drawing, or it may be installed on the vertical portion of the closet elbow, next to the 15 closet tank. For purposes of illustration I have shown the horizontal position of the multiple joint extension union in connection with a closet spud, and closet elbow.

My invention may also be used on closet offsets, tubing trap extensions, and on T's in connection with bath wastes and overflows. It will enable one to move a bath tub into and out of position without raising the tub to set the waste and overflow onto the outlet stub. It will also 25 enable one to remove the T on a bath waste and overflow, for repairs and cleaning the waste line, without removing the tub.

It may also be used on radiator connections where the stubs have been roughed-in too far 30 apart.

All of the foregoing and still further objects and advantages of the invention will become apparent from a study of the following specification, taken in connection with the accompanying drawing 35 wherein like characters of reference designate corresponding parts throughout the several views, in which:—

Figure 1 shows a horizontal cutaway section showing the multiple joint extension union in position, connecting a closet elbow with a closet spud, with gaskets.

Figure 2 shows a horizontal cutaway section showing the union extension nut removed from the closet spud, and the extension sleeve with- 45 drawn. The gaskets being removed.

Figure 3 shows a plan view of the union extension nut.

Figure 4 shows the union extension nut in vertical position, half in section.

Figure 5 shows the extension sleeve in vertical position, half in section.

Figure 6 shows another type of extension sleeve in vertical position, half in section.

Referring to the drawing:—

55 The numeral 1 represents a closet elbow partly

cut away to show a section. Numeral 8 represents a closet spud partly cut away to show a section. Numeral 9 represents the closet spud lock nut partly in section which is threadedly attached to the closet spud 8. The union extension 5 nut designated as 10 is supplied at one end with a female thread 11 for threadedly mounting onto the male thread 12 of the closet spud 8.

The numeral 13 represents a cylindrical extension sleeve having a female end 14 and a male 10 end 15. The interior of the female end 14 of Figure 5 is adapted to slidably engage the exterior end of the closet elbow 7. The exterior of the male end 15 is made the same diameter as the exterior of the closet elbow 7 for slidably 15 engaging the inside diameter of the closet spud 8. The cylindrical portion 16 of the union extension nut 10 is smoothly bored and adapted to slide over the external diameter of the female end of the extension sleeve 13. The inverted flange 17 forming one end of the union extension nut 10, and the end 18 of the extension sleeve 13 together with the outside diameter of the closet elbow 7 form an annular retainer for the gasket or packing 19. Likewise, the shoulder 20 of the extension sleeve 13 and the end 21 of the closet spud 8 together with the outside diameter of the male end 15 of the extension sleeve form an annular retainer for the gasket or packing 22.

It will be noted by the above explanation, and 30 a study of the drawing in Figure 1 that the sleeve 13 forms an extension of the closet elbow 7, slidably engaging the closet elbow with the closet spud 8, the union extension nut completely covers the sleeve 13 and is threadedly attached to 35 the closet spud 8. The two annular retainers each packed with gaskets or suitable packing are also covered by the union extension nut. By tightening the union extension nut rotatively on the closet spud, the packing in the annular retainers is compressed and both joints are made leakless in one operation.

In Figure 2 it will be noted that by removing the union extension nut and slidably drawing back the extension sleeve to the position shown 45 that the closet elbow is free from the closet spud and either may be removed.

In Figure 6, the interior of the female end 14 of the extension sleeve, as will be noted is enlarged over that shown at 14 in Figure 5. The 50 end 18 of the extension sleeve in Figure 6 is inwardly flanged to slidably fit the exterior of the closet elbow 7. The object of enlarging the interior of the female end 14 in Figure 6 is for the purpose of relieving any strain which may be 55

encountered due to the members to be joined being out of alignment. With the enlargement of 14 in Figure 6 the closet elbow could enter the extension sleeve at a considerable angle, and a 5 tight compression joint successfully made between the inverted flange 17, and the end 18 of the extension sleeve in Figure 6 without strain.

It is believed that the many advantages of the 10 multiple joint extension union in accordance with the present invention will be readily understood, and although the preferred embodiment of the invention is as illustrated and described, it is to be understood that changes in the details of construction and in the combination and arrangements of parts may be resorted to which 15 will fall within the scope of the invention as claimed.

What is claimed is:—

1. A multiple joint extension union, for connecting tubing with an existing exteriorly threaded fitting, comprising in combination an elongated 20 slideable nut, smoothly bored, having on one end an inverted flange, the inner edge of the flange to slidably fit the tubing to be connected, and threaded interiorly in the remaining end to fit the said existing exteriorly threaded fitting, an extension sleeve, having one end slideable exteriorly over said tubing, and the opposite end of said sleeve slideable interiorly of the said existing fitting, annular means arranged for gaskets, and means provided on the slideable nut for tightening said gaskets.

2. A slideable extension sleeve, for insertion between two existing members to be joined together, said extension sleeve slideable exteriorly over one existing member and interiorly slideable in the other existing member, said extension sleeve surrounded with an elongated smoothly bored slideable nut having on one end an inverted flange and threaded interiorly on the remaining 40 end for attachment to one existing member, annular means provided for making water tight joints between said extension sleeve and existing members to be joined, and means provided on the slideable nut for tightening said extension sleeve in position.

3. A multiple joint extension union for connecting plain cylindrical tubing with an exteriorly threaded smoothly bored fitting, comprising in combination an extended nut smoothly bored for the greater part of its length, having 50 on one end an inverted flange adapted to slidably engage said plain cylindrical tubing interiorly threaded in its remaining end for engaging said exteriorly threaded fitting, and a tubing extension sleeve adapted to slidably engage the exterior of said plain cylindrical tubing with the greater part of its length, the remaining portion of its length concentrically reduced, said reduced 55 portion adapted to slidably engage the interior of said exteriorly threaded fitting, said extension nut adapted to completely envelope said extension sleeve, means provided for two compressible annulars and means provided on said nut for 60 rotatively compressing tightly the two compressible annulars simultaneously.

4. A multiple joint extension union for connecting two members in fixed relation to each other, one member having a plain exterior end, 70 the other member having a threaded exterior end and smoothly bored interior, said multiple joint extension union comprising in combination a concentrically reduced sleeve adapted to slidably increase the length of said plain member, said 75 sleeve extending to co-operate with the interior

of said exteriorly threaded member and an extended union nut adapted to completely envelope said sleeve, said nut having in one end an interior thread for engaging said exterior threaded member, and an inverted flange on the remaining end for urging said sleeve forward to a rigid position as said nut is rotatively screwed on to said exterior threaded member, means provided for two compressible annulars and means provided on said nut for successively tightening both of said compressible annulars.

5. A multiple joint extension union for connecting a closet bowl spud in distant relation with a closet flush elbow comprising in combination a tubular sleeve adapted for the greater part 15 of its length to slidably fit the exterior end of said closet flush elbow, concentrically reduced at its opposite end to slidably enter the smooth interior of said closet bowl spud, said tubular sleeve forming an extension to said closet flush elbow, 20 and an extension nut, completely enveloping said tubular sleeve in its intermediate position, said extension nut threaded interiorly at one end to engage the threaded exterior of said closet bowl spud, an inverted flange on its opposite end, 25 means provided for two compressible annulars, and means provided on said extension nut for rotatively compressing said annulars simultaneously and successively, forming positive leakless joints between said sleeve, closet bowl spud and 30 closet elbow.

6. A tubular extension sleeve for slidably increasing the length of plain tubing forming an intermediate between two members to be joined together, said members being in fixed position 35 and distantly related, said extension sleeve expanded concentrically for the greater part of its length and adapted to slide exteriorly over one of said members, the remaining portion of said sleeve adapted to slide interiorly of the other 40 of said members, an extension coupling adapted to encase said extension sleeve, having on one end an inverted flange for slidably engaging one of said members, threaded interiorly in the remaining end for engaging the threaded exterior 45 of said other member, the expanded portion of said extension sleeve forming a spacer between two compressible annulars enveloped within said extension coupling, means provided on said coupling for tightly compressing rotatively both 50 annulars simultaneously and successively.

7. A multiple joint extension union for connecting plain cylindrical tubing with exteriorly threaded tubing wherein said plain cylindrical tubing has an exterior diameter smaller than 55 the interior diameter of said exteriorly threaded tubing, said multiple joint extension union comprising in combination a concentrically reduced sleeve adapted to slidably increase the length of said plain cylindrical tubing, said sleeve extending into the interior of said exteriorly threaded tubing, and an extended nut adapted to completely envelope said sleeve, said nut having in one end an interior thread for directly engaging 60 said exteriorly threaded tubing, and an inverted flange on the remaining end for directly compressing two thin compressible annulars interposed within said nut, means provided on said nut for rotatively urging said sleeve forward into 65 said exteriorly threaded tubing, means for tightening said compressible annulars simultaneously and successively, forming two positive leakless joints.
